UNITED STATES PATENT OFFICE.

JOSIAH B. CHASE, OF NEWTON, MASSACHUSETTS, ASSIGNOR TO THE BALL AND SOCKET FASTENER COMPANY, OF NASHUA, NEW HAMPSHIRE, AND BOSTON, MASSACHUSETTS.

DETACHABLE FASTENER.

SPECIFICATION forming part of Letters Patent No. 651,434, dated June 12, 1900.

Application filed August 8, 1898. Serial No. 688,127. (No model.)

To all whom it may concern:

Be it known that I, JOSIAH B. CHASE, a citizen of the United States, residing at Newton, in the county of Middlesex and State of Massachusetts, have invented a new and useful Improvement in Detachable Fasteners, of which the following is a full, clear, and exact description, reference being had to the accompanying drawings, forming a part of this specification, in explaining its nature.

This invention relates especially to the socket member of a detachable fastener.

It consists in the combination of a metal gromet applied to the thing or fabric with which the fastener is employed (and which may or may not be a holding-gromet in the sense that it may receive the draft on the ball) and a socket-piece, which is independently attached upon the outer surface of the thing or fabric with which the socket member is used and which has a yielding socket-entrance and a wall surrounding the socket-entrance, the whole being surrounded by an attaching-flange, the arrangement of these parts being such that the socket-entrance will normally stand substantially in line with the opening through the fabric or gromet, so that the ball member when inserted through the opening will enter the socket-entrance. This socket-piece is like that described and claimed in Letters Patent No. 604,637, granted May 24, 1898; but in the present invention it is so used that engaging access to the socket-entrance may only be obtained through a hole or perforation in the material through which the ball member must be passed to make engagement with said socket-entrance, thus differing from the use shown in said patent, where its raised wall bears against the surface of the fabric or thing, so that its socket-entrance is presented away from said surface and the fabric is not perforated. In the present case the socket-piece may take the entire strain, in which case the gromet will serve as a binding and finish for the hole and also as a stay or reinforcement to the socket-entrance, or the socket-piece may serve as a spring-holder to prevent the easy withdrawal of the ball member, in which case the gromet

will be mainly relied upon to withstand lateral draft, these differences of action depending somewhat upon the relative dimensions of the parts and also upon the firmness of the material to which they are applied.

In the drawings, Figure 1 is a view in plan of a strap, representing its ends disengaged and provided one with a ball member and the other with a socket member. Fig. 2 is a view, also in plan, representing the two ends of the strap as attached by the engagement of the two members of the fastener. Fig. 3 is a view in section on the dotted line 3 3 of Fig. 2. Fig. 4 is a view in section upon the same line of the attached socket member without the ball. Fig. 5 is a view in plan, inverted, of the attached socket member. Fig. 6 is a view in plan of the inner face of the gromet. Fig. 7 represents the two parts or sections from which the gromet is made. Fig. 8 is a view in section showing the relative relation of parts when the socket-piece is acting to prevent separation of the two members while the gromet is withstanding the lateral draft. Fig. 9 represents in plan a socket-piece having three slits, none of which extend through the flange.

Referring to the drawings, A is the ball member of the fastener and preferably has the wide perforated attaching-flange a , by which it may be attached by sewing to the face of the thing or fabric with which it is used.

B is the socket member. It comprises the metal gromet b , applied about the edge of the hole b' in the thing or fabric to which the socket member is attached, and which provides the hole with the metal edge b^2 and the continuous metal protecting-flange b^3 upon the under surface of the thing or fabric and the flange b^4 upon the upper or outer surface of the thing or fabric.

C is the socket-piece. It has the socket-entrance c , preferably yielding, the flange c' , having perforations c^2 , by means of which it is attached to the outer face of the thing or fabric, and the double wall c^3 , which extends from the socket-entrance outward and inward, forming the ball-holding cavity c^4 and a raised wall c^5 about it. This socket-piece is

secured to the thing or fabric, as represented in Fig. 3, to bring the socket-entrance concentrically in line with the hole b' and with its wall c^5 outermost and the socket-entrance c innermost. It also covers the flange b^4 of the gromet.

I prefer to make the gromet of the two parts represented in Fig. 7, the eyelet d providing the finishing-flange b^8 , the binding or metal edge b^2 , and the fastening extension b^5 and the part b^4 being in the nature of an inner washer, which may be slightly dished and upon which the fastening extensions b^5 are turned. (See Fig. 6.)

15 In attaching the socket member the material is first provided with a hole, the gromet set to bind the hole, and the socket-piece C placed over the gromet, with its socket-entrance concentrically in line with the hole thereof, its wall c^5 extending outward, and its flange bearing against the material beyond the outer edge of the flange b^4 of the gromet, the flange being secured to the material. The cavity formed by the wall c^5 may receive the 25 gromet in part or the portion b^4 . In inserting the eyelet d the walls will usually become slit, as shown in Fig. 6.

In Fig. 3 I have represented the neck of the ball as in engagement with the socket-entrance when under strain and in Fig. 8 as in engagement with the gromet. To engage the members, the ball is passed through the hole in the gromet and through the socket-entrance into the socket-cavity, as in Fig. 8, or directly 35 into the socket-entrance and into the socket-cavity, as in Fig. 3, and the neck of the ball may bear against the edge of the socket-entrance or the edge of the gromet when the members are subjected to lateral draft.

40 The invention is especially applicable to the larger and heavier uses—such, for instance, as horse-blankets, surcingles and large straps of that character, heavy curtains, like the curtains of sleeping-cars, &c. Under such circumstances the fact that the wall c^5 projects outward enables the socket-piece to form a chamber within which the gromet will lie, as will be understood from Figs. 3 and 4, so that the thickness of the gromet will not add to 45 the thickness of the socket member.

In Fig. 9 there is shown a socket-piece which has a continuous flange, the resiliency being obtained by slits extending from the edge of the piece at the socket-entrance into 50 or through the wall surrounding the socket-entrance but not extending through the flange. This provides a structure with a stiffer flange than that in which the slit extends through the flange and is of value for 55 the reason.

Having thus fully described my invention I claim and desire to secure by Letters Patent of the United States—

1. The combination of an article or fabric

having a hole formed therein with a socket-piece having a yielding socket-entrance located about said hole, a fastening-flange adapted for attachment to said article independent of said hole, and a wall interposed between said socket-entrance and said flange 65 and projecting upward away from the surface of said fabric and said flange, and said socket-entrance projecting downward from the upper portion of said wall toward said hole and being located to receive the ball 75 member of a fastener when projected through said hole.

2. An article or fabric having a hole and provided with a metal gromet binding the edge of said hole and forming a finishing-flange b^8 to its under surface, in combination with a socket-piece C attached to the upper surface of the article or fabric independently of said gromet and having a fastening or attaching flange, a raised wall and a socket-entrance located substantially in line with the hole in said gromet, as and for the purposes set forth.

3. In a separable fastener, a ball member in combination with a socket member consisting of a socket-piece, a hole in the article or fabric to which said socket-piece is attached and a metal gromet binding said hole, said socket-piece being attached to the surface of said material independently of said 95 gromet and surrounding said gromet and located upon the upper side of said hole, and being provided with a socket-entrance in line with said hole adapted to engage the ball of the ball member after it has been passed 100 through said hole, as and for the purposes set forth.

4. The combination in a socket member of a separable fastener, of a socket-piece adapted to engage the ball member of a fastener 105 in or through a hole in the fabric to which the socket-piece is secured, and a metal binding for said hole said socket-piece and said metal binding being attached to the fabric independent of each other, as and for the 110 purposes set forth.

5. In the socket member of a separable fastener, the combination of a socket-piece adapted to engage the ball member of the fastener in or through a hole in the fabric, 115 to which the socket-piece is independently secured, and a gromet binding said hole, said socket-piece being provided with a socket-entrance, an attaching-flange and a wall lying between said entrance and said attaching-flange, said wall being raised from the fabric 120 and forming a chamber within which said gromet may lie, as and for the purposes set forth.

JOSIAH B. CHASE.

In presence of—

J. M. DOLAN,
L. A. WALSH.
